UNITED STATES PATENT OFFICE.

WALTER T. MARTIN, OF DANVERS, MASSACHUSETTS.

BOOT OR SHOE.

SPECIFICATION forming part of Letters Patent No. 351,186, dated October 19, 1886.

Application filed September 26, 1884. Serial No. 144,030. (No model.)

To all whom it may concern:

Be it known that I, WALTER T. MARTIN, of Danvers, Massachusetts, have invented a new and useful Improvement in Boots and Shoes, of 5 which the following is a specification.

The invention consists, broadly, in a backing formed of a single piece of leather extending from above the ankle of the boot or shoe to the heel proper, narrow at the ankle-joint 10 and spreading or flaring below, and having at the bottom a V-shaped cut sewed up, so that the said backing may readily conform to the rear contour of the boot when the boot is lasted, and so that the completed boot shall not break 15 or crack at the ankle-joint in wear.

The invention does away with the seam at the rear of the boot or shoe, usually formed by stitching together the quarters, and the boot or shoe is much more flexible than when made 20 according to the common method.

A part of the present invention relates to a specific construction, in which use is made of the said broad feature of the invention; and this part of the invention consists in inserting 25 at the rear of the boot or shoe between the two side pieces or quarters a third piece or backing, which is narrow at the ankle and flaring below, and is shaped to correspond 30 to the rear contour of the last by cutting a V-shaped piece out of the bottom, and then stitching together the sides of the V-shaped opening thus made. When the boot or shoe is finished, the seam thus formed will be in the 35 part of the boot or shoe where flexibility is not required.

In the drawings, I show at Figure 1 the two side pieces or quarters, A and B, and the third piece or backing, C, which is to be inserted between the side pieces or quarters, the said 40 third piece or backing having the V-shaped piece cut from the bottom. At Fig. 2 the same three pieces are shown stitched together,

and with the V-shaped opening in the third piece closed by stitching. Fig. 3 represents a boot made according to my invention. 45

It will be observed that the rear edge of the quarters or side pieces, A and B, is cut so that it shall correspond to the adjacent edge of the backing-piece C after the latter is bent to shape. 50

In the manufacture of the boot represented in my application No. 144,021, filed herewith, instead of thus cutting the quarters and inserting a piece to form the back of the boot or shoe, I cut them and stitch them together in 55 the usual manner upon a curve corresponding to the rear contour of the boot, and re-enforce them upon the outside by a stay or backing having the essential characteristics of the inserted piece of the present application, and in 60 my application No. 144,022 I show how a similar stay or backing piece may be applied to a boot or shoe whose quarters are cut in one piece and themselves shaped to the last below the ankle in the same manner as the stay or 65 backing piece. Such modifications and others are obviously within the first claim of the present invention.

I claim—

1. In a boot or shoe upper, the backing 70 formed of a single piece, narrow at the ankle-joint and wide below, the said wide portion containing a V-shaped cut sewed up, substantially as described.

2. In a boot or shoe upper, the combination, 75 with the quarters or side pieces, A and B, of the piece C, narrow at the ankle-joint and wide below, and contracted and shaped at the bottom, substantially as described.

WALTER T. MARTIN.
